UNITED STATES PATENT OFFICE.

ADELBERT J. DOUGLASS, OF ILION, NEW YORK.

CRAYON-RACK FOR BLACKBOARDS.

SPECIFICATION forming part of Letters Patent No. 404,389, dated June 4, 1889.

Application filed December 8, 1888. Serial No. 293,039. (No model.)

To all whom it may concern:

Be it known that I, ADELBERT J. DOUGLASS, a citizen of the United States of America, residing at Ilion, in the county of Herkimer 5 and State of New York, have invented certain new and useful Improvements in Crayon-Racks, of which the following is a specification, reference being had therein to the accompanying drawings.

10 My invention pertains to an improvement in crayon or chalk racks or shelves for blackboards; and it consists in the peculiar structure, combination, and arrangement of parts, substantially as hereinafter more fully shown 15 and described.

In the accompanying drawings, Figure 1 is a view in perspective of my invention. Fig. 2 is a plan view thereof. Fig. 3 is a vertical section showing the rack thrown up, and Fig. 20 4 is a detail view thereof.

The object of my invention is to provide, in connection with the ordinary blackboard tray or receptacle for the dust which falls from crayons and erasers when used upon 25 blackboards, an adjustable rack upon which to rest the crayons and erasers, and which may be thrown back out of the way for cleaning the dust from the dust-tray, and tightly closed down again upon removal of the dust.

30 One feature of my invention is the facility with which the crayon-rack A may be secured to the dust-tray of any ordinary blackboard by hinging rack A to the top of the beveled wall or front rim B of the dust-tray by means 35 of the staples a, as shown. This enables the rack to be readily tipped back from over the dust-tray for convenience of removing the dust therefrom.

The crayon-rack A consists of a wire gauze 40 or netting having its front edge b turned up at right angles, and its inner edge b' turned down oppositely thereto and outwardly and obliquely inclined, its front upturned edge b serving as a fender as against the accidental 45 falling off therefrom of crayons and erasers, and its inner downturned edge b' serving

as a standard or support to hold the rack in horizontal position.

The spring C (one or more of which may be used) is formed of a single wire having its 50 vertical ends C secured in coincident orifices in the bottom of the dust-tray, and its horizontal part slightly bowed to project outwardly, as shown.

The turned-down edge of the crayon-rack 55 A, which is inclined at an angle outwardly from the blackboard, as aforesaid, is arranged to press against and to gradually retract springs C in closing down the rack over the dust-tray, and when rack A has passed 60 springs C the springs recoil and hold the rack securely in position, thus preventing accidental or unnecessary tipping of the rack. Rack A may also, when desirable, be provided with lateral turned-down edges fitting 65 at either end of the dust-tray, and light strips of wood in lieu of the metallic fender and support may also be used. Thus constructed my crayon-rack, which is inexpensive, may be correctly adjusted to any required dimensions and readily attached to the dust-tray 70 of any ordinary blackboard.

I claim—

The crayon-rack consisting of the crayon or chalk screen, the dust-trough, and the 75 springs, the screen comprising a series of transverse wires bent down to form a vertical leg for the support of the rear edge of the tray and upward to form a guard at the front edge of the tray, said springs being formed 80 with vertical end portions secured in the bottom of the trough, and with a horizontal portion bowed to project outward to secure the screen in place, substantially as shown and described, and for the purpose set forth. 85

In testimony whereof I affix my signature in presence of two witnesses.

ADELBERT J. DOUGLASS.

Witnesses:

T. F. THOMAS,
GEO. C. HUTCHINS.
